ABSTRACT OF THE DISCLOSURE

A process for the separation of n-paraffins from hydrocarbon distillate by means of powdered urea is provided, wherein hydrocarbon distillate is treated in the presence of an activator solvent of methanol and aromatic hydrocarbon together with powdered urea, and then resulting urea adduct is separated from the liquid part of the reaction mixture. The adduct is then washed with aromatic hydrocarbon, and decomposed by heating in a decomposition medium consisting of 5 to 30 percent by volume of n-paraffins and 70 to 95 percent by volume of aromatic hydrocarbons. The thus obtained urea is then separated from the n-paraffin product, and is recycled into the process.

BACKGROUND OF THE INVENTION

The present invention relates to the method of separating n-paraffins of high purity from hydrocarbon oils, in particular from middle distillate fractions of petroleum, which have a boiling point over the range of about 100° C. to 440° C.

Numerous methods of lowering the pour point of lubricating oil stocks by treatment with solid urea have been proposed in the prior art. For example U.S. Patent 2,911,350 (1959) discloses such a process. However the main object of these methods is to lower the pour point of lubricating oil stocks, and problems concerning both the purity of the n-paraffins obtained after the decomposition of adduct, and the method of n-paraffin recovery have almost been neglected.

There are many methods of urea adduction using an aqueous solution of urea for extracting n-paraffins from middle distillate, but the disadvantage of these processes is that the purity of the thus-extracted n-paraffins is low, because oil components other than n-paraffins solubilize in the water phase which is coexistent with the n-paraffin adduct, and extreme contamination by these components is found in the product obtained after decomposition of the adduct.

BRIEF SUMMARY OF THE INVENTION

The principal object of this invention is to provide a method of extracting n-paraffins in substantially high purity and in good yield by means of urea adduction technique using solid or powdered urea.

Another object of the invention is the provision of a method for extracting n-paraffins using urea wherein the disadvantages present in the prior art processes have been eliminated.

Another object of the present invention is to provide

2

effective activators for urea adduction, thereby improving the effectiveness of adduct decomposition.

Still another object of the present invention is to provide a continuous adduction process which is more economical than hitherto proposed processes.

A particular object of this invention is the provision of a method for obtaining high purity n-paraffins in high yield from middle distillates, such as kerosene or gas oil fractions of petroleum oil.

It has been discovered that these and other objects can be attained by an improved process for production of n-paraffins from a liquid petroleum fraction by urea adduction, which comprises treating hydrocarbon oil with solid urea in presence of an activator solvent which consists of a mixture containing methanol and aromatic hydrocarbon, wherein methanol is present in an amount of 3 to 30 percent by volume.

According to the invention, the n-paraffin product is obtained by the further steps of separating the resulting adduct from the liquid portion of the reaction mixture, washing the thus-obtained adduct with aromatic hydrocarbon, decomposing the adduct by treatment with 1.5 to 5.0 volumes of a decomposition medium per volume of said adduct, the decomposition medium consisting of 5 to 30 percent by volume of n-paraffins, preferably n-paraffin which have been previously extracted and the balance being aromatic hydrocarbon, at a temperature of above 60° C. but below the dissociation temperature of said adduct.

30 BRIEF DESCRIPTION OF THE DRAWING

The figure represents a schematic flow diagram of a plant for the separation of n-paraffins from hydrocarbon distillate and illustrates a continuous process according to the present invention.

35 DESCRIPTION OF THE PREFERRED EMBODIMENT

In accordance with the present invention, liquid hydrocarbon containing n-paraffins is treated with solid urea in presence of the activator solvent which consists of a mixture of methanol and aromatic hydrocarbon, the methanol being present in an amount by volume of 3 to 30 percent and aromatic hydrocarbons making up the remaining volume. During the step of forming the urea adduct, desirably the mixture of hydrocarbon charge oil, urea and activator solvent are vigorously agitated. The aromatic hydrocarbon used for the activator solvent may be a single compound or a mixture of two or more compounds and is preferably selected from aromatic hydrocarbons having 6 to 8 carbon atoms, such as benzene, toluene, xylene and ethylbenzene. The amount of the activator used is preferably 5 to 40 percent by volume based on the volume of hydrocarbon oil, and as this activator solvent is completely soluble in the oil phase, the time required to reach the adduct equilibrium is in the range of five to eight minutes. Thus, the time required for adduction time is in strong contrast to that required for a conventional process using methanol alone.

In the case of conventional processes, methanol tends to form a separate phase upon the oil, and the time required to reach the adduction equilibrium is thirty minutes or more because of the difficulty of diffusion of methanol in hydrocarbon oil. Generally speaking, normal paraffins obtained by the urea adduction method using solid urea are superior in purity to that obtained

by methods using a solution of urea, such as an aqueous solution thereof, but isoparaffins such as 2-methyl-paraffins are adductable and some quantity of these isoparaffins remains in the extracted portion as contaminant. It is in such cases that the improvement in the purity of the product n-paraffins which results from the method of the present invention is most advantageous.

The present invention provides that one volume of adduct thus obtained is then retreated with 1.5 to 5 volumes of a contact oil which is comprised of n-paraffins; preferably the n-paraffins used for this step of the process are those obtained from previous extraction of charge hydrocarbon oil; or, the adduct may be retreated with the same amount of a contact oil which is comprised of hydrocarbon charge oil. It has been found that an improvement in purity of at least 0.5 percent by weight is obtained, and in some cases an improvement of more than 1 percent by weight is obtained without detriment to the recovery of n-paraffins by the present method.

The present process is useful for separating n-paraffins from hydrocarbon distillates ranging from kerosene to gas oils. Thus hydrocarbon fractions which having a boiling point of about 100° C. to about 440° C. may be subjected to treatment in accordance with this invention. Hydrocarbon distillate may be used by itself as the charge oil or it may be mixed with deparaffined oil before being treated.

The following example illustrates the method of the present invention and also shows the effect on the product of different treatments of the urea adduct.

EXAMPLE 1

Part A.—1 kg. of a kerosene fraction from Middle East Crude which has a n-paraffin content of 11 percent by weight and a boiling range of 135° to 268° C. was mixed with toluene-methanol solvent containing 10 percent by volume of methanol, and 408 g. of powdered urea was added thereto, and the mixture was stirred for ten minutes at 20° C. After the filtration of adduct slurry by suction, adduct was washed with 2,300 ml. of toluene and was decomposed with 1850 ml. of decomposition medium consisting of 80% by volume of toluene and 20% by volume of n-paraffin at 80° C. After stirring for ten minutes, the regenerated urea was separated from the n-paraffins at the second filtration step, 405 g. of product n-paraffins were obtained, after the evaporation of toluene, which represents a yield of 10.8 percent by weight based on the weight of said kerosene after subtraction of the weight of n-paraffin added in decomposition medium. The n-paraffins thus obtained had a purity of 97 percent by weight in accordance with gas liquid chromatography as shown in Table 1.

Part B.—The same adduct was washed with 5,350 ml. of toluene and 377 g. of n-paraffins, and the product n-paraffins were then obtained using the same treatment as mentioned above with the result that 8 percent by weight of n-paraffin were recovered having a purity of 97.3 percent by weight.

Part C.—The same adduct was contacted with 2,330 ml. of a mixture consisting of 40 percent by weight of n-paraffins and 60 percent by weight of kerosene, stirred for ten minutes, filtered, and then the thus-retreated adduct was washed with 3,050 ml. of toluene, after the above mentioned treatment, 407 g. of n-paraffin were obtained, with a recovery rate of 11.0 percent by weight, and purity of 98.2 percent by weight.

Accordingly, a substantial improvement in recovery and purity of n-paraffins is obtained by the retreatment step of the invention illustrated in part C of this example whereas the use of an increased amount of washing solvent for washing the adduct as illustrated in part B of this example results in a larger decrease in the recovery rate of the n-paraffins. These results are summarized in Table 1.

TABLE 1

While it might be expected that the concentration of n-paraffins in the oil should be as high as possible for the most effective process, particularly with respect to the contact "retreatment" or "rewashing," it has been found that there is no marked difference in the effect of the concentration between 5 and 90 percent by weight of n-paraffins in the oil, and 10 to 40 percent by weight seems to be preferable. An adequate quantity of the contact oil was found to be 1.5 to 5 volumes per volume of adduct. Substantially pure substances such as n-paraffins or the mixture of n-paraffins and pure aromatic or naphthenic hydrocarbons may be used instead of the contact oil mentioned above. Paraffinic hydrocarbons which have different numbers of carbon from those in the charge oil may also be used as contact oil. Normal paraffins from charge hydrocarbon oil, or those which have the different carbon number from the former are also used as a contact oil. The required contact time in this case is from about 5 to about 30 minutes or more, preferably from 10 to 30 minutes, and temperature range of from 10° to 40° C. is preferred.

Deparaffined oil which has been obtained by the preceding adduction step is used as a diluent oil for adduction, to aid the transportation of adduct slurry.

Adduct decomposition in this invention is carried out at the temperature below the dissociation temperature of adduct, which has been determined by the method of Knight et al. (H. B. Knight et al., Anal. Chem. 24 1331 (1951)). It has been found that in all cases, a decomposition of 60° C. to 120° C. is effective, using a decomposition medium consisting of a mixture of the extracted n-paraffins and aromatic solvent, such as benzene, toluene, xylene and/or ethylbenzene. The concentration of n-paraffin in the decomposition medium may be from 5 to 30 percent by volume, preferably 10 to 20 percent by volume, and the decomposition temperature is preferably from 70° C. to 90° C. The contact time required for the complete decomposition of adduct to solid urea and n-paraffins is from 8 to 10 minutes under the above mentioned conditions, and it is necessary to add 1.5 to 5 volumes of decomposition medium to one volume of adduct from considerations of the transportation of the urea slurry and the decomposition rate of adduct.

The following example illustrates the decomposition of the urea adduct to obtain the n-paraffin product in accordance with the present invention.

EXAMPLE 2

n-Cetane (n-hexadecane) urea adduct, which has a dissociation temperature of 111.7° C. and a weight ratio of urea to n-cetane in the adduct of 3.8 was decomposed with 4 volumes of a medium containing 10, 30, and 50

percent by volume of n-cetane, respectively, while being stirred for 20 minutes at 80° C. A part of slurry which had undergone decomposition was filtered and the regenerated urea portion washed with a large quantity of toluene and examined by x-ray diffraction.

Several powder patterns are summarized in Table 2, where (S), (VS), (W) and (VW) means a diffraction intensity which is strong, very strong, weak, and very weak, respectively. It is evident from these powder patterns that complete decomposition was obtained when the concentration of n-cetane was 10 and 30 percent by volume and the diffraction patterns are quite similar to those of pure urea itself, but in case wherein the medium contained 50 percent by volume of n-cetane, an undecomposed portion of adduct remained.

TABLE 2

Diffraction angle of n-cetane urea adduct (20)	Diffraction angle of pure urea (20)	Diffraction angle of the samples (20) (Volume percent of n-cetane in decomposition medium)		
		(100)	(30)	(50)

The especially preferred method of the present invention is a continuous process for separating n-paraffins from a petroleum fraction which will be described in the following example with reference to the accompanying drawing.

EXAMPLE 3

Gas oil 2, containing 18 percent by weight of n-paraffins and having boiling range of 190° to 270° C. is charged in an amount of 11,800 kg./hr. through line 3 where it is diluted with 17,700 kg./hr. of deparaffined oil 4 which has been obtained by previous adduction of the charge oil; 2,500 kg./hr. of a toluene-methanol mixture 6 as the activator solvent, containing 10 percent by volume of methanol is also fed together with said oil mixture through line 3 to the reactor 7 which is provided with agitation means adequate to provide vigorous liquid-solid mixing; 8,700 kg./hr. of recycled urea 8 is also charged into reactor 7 through line 3. The slurry of urea-n-paraffin adduct is discharged from reaction vessel 7 through line 9 and sent to a solid-liquid separator 11 which is equipped with means for separating the urea adduct from the unreacted liquid such as a suction filter or a centrifuge. After the adduct is separated, it may be washed in the solid-liquid separator 11 with a liquid aromatic hydrocarbon 10, toluene being used in this process, and after being washed, the adduct may be sent through lines 13 and 15 directly to the decomposition vessel 17, if the purity of n-paraffins produced in this way is satisfactory. If a higher purity product is desired, the adduct separated in the solid-liquid separator 11 is sent by way of line 13 to the retreatment vessel 19 which is provided with means for agitation. The liquid filtrate from the solid-liquid separator 11 is discharged through line 21 and sent to storage vessel 23. From storage vessel 23 the filtrate is sent to the solvent recovery tower 25; the distillate from the top of tower 25 is sent through line 27 to distillation tower 29, a mixture of toluene and methanol being collected from the top of tower 29 and toluene from the bottom. The bottoms from the solvent recovery tower 23 is sent through line 31 to distillation tower 33; toluene is recovered from the top of tower 33 and deparaffined oil from the bottom.

Contact oil 34, in an amount of 24,000 kg./hr. is also charged from line 35 to line 13 and into the retreatment vessel 19 where it is agitated with the adduct. 75

The contact oil is charge oil, or a mixture of charge oil and n-paraffins which have been separated previously from the charge oil. The slurry of adduct and charge oil is discharged from vessel 19 through line 37 and sent to the solid-liquid separator 39, where the adduct is separated from the contact oil by means such as filtration or centrifugation and is then washed with about 30,000 kg./hr. of toluene 40. The solid-liquid separator 39 is equipped with means such as a trunnion valve for discharging separately, the filtrate from the separation of adduct and contact oil, the filtrate from washing the adduct, and the washed adduct. Thus, the washed adduct exits from the solid-liquid separator 39 through line 41 and is then sent to the decomposition vessel 17 which is equipped with heating means and agitation means. The filtrate from the separation of the adduct and the contact oil in the solid-liquid separator 39 is withdrawn through line 43 and sent to the storage vessel 45, and the toluene wash from the solid-liquid separator 39 20 exits through line 47 and is sent through line 21 to storage vessel 23. Through line 41, 24,000 kg./hr. of a recycled mixture of 4 volumes of toluene and 1 volume of n-paraffins is also charged into the decomposition vessel 17. The mixture of toluene and n-paraffins are sent to line 41 from storage vessel 49, through line 51. The adduct is then decomposed under continuous agitation and heating in the decomposition vessel 17 at a temperature of 75°-80° C. Then, the regenerated urea in the form of a slurry is withdrawn from the decomposition vessel 17 through line 53 and is fed to solid-liquid separator 55 which is equipped with solid-liquid separating means, where the urea is separated and is then washed with 9,000 kg./hr. of toluene 56, after which the urea is withdrawn and recycled through line 3 into the reactor 7. Thus the adduction cycle is repeatedly continued. The liquid portion from the solid-liquid separator 55 contains toluene and n-paraffins and is sent through line 57 to storage vessel 49 from where it may be fed through line 51 to the decomposition vessel 17, or fed to solvent recovery tower 59. The top fraction from the solvent recovery tower 59 is fed through line 61 to the distillation tower 33 and bottom fraction from the solvent recovery tower 59 is fed through line 63 to distillation tower 65, where the toluene is distilled off and recovered. Normal paraffins are collected from the bottom of distillation tower 65 at the rate of 2,240 kg./hr. and are stored in vessel 67. If desired, a portion of n-paraffin stored in vessel 67 may be sent through line 69 to be mixed with the contact oil charged into the retreatment vessel 17 through line 35; also a portion of the filtrate withdrawn from the solid-liquid separator 39 through line 43 may be added to the contact oil through lines 71 and 69.

The contact oil which has been separated as filtrate in the solid-liquid separator 39 and then stored in vessel 49 is fed through line 73 as charge stock 2. Deparaffined oil is produced at the rate of 9,370 kg./hr.

Thus an economical method for separating n-paraffins from hydrocarbon oil where the n-paraffins are obtained in high purity and in high yield has been provided by the present invention. While the invention has been described by reference to particular examples, many modifications and variations in the operating pressures which will be apparent to those skilled in the art may be made without departing from the scope and spirit of this invention.

What we claim and desire to secure by Letters Patent is:

1. A process for the separation of n-paraffins from a distillate hydrocarbon oil by means of powdered urea, which comprises

(a) treating said hydrocarbon oil with said urea in the presence of an activator solvent consisting essentially of 3 to 30 percent by volume of methanol and 70 to 97 percent by volume of aromatic hy-

drocarbon having from 6 to 8 carbon atoms per molecule, said activator solvent being present in an amount of 5 to 40 percent by volume based on the volume of said hydrocarbon oil,

(b) separating the thus-formed urea adduct from the liquid mixture,

(c) washing said adduct with said aromatic hydrocarbon,

(d) decomposing said adduct by heating a mixture of said adduct and 1.5 to 5.0 volumes per volume of said adduct in a decomposition medium consisting essentially of 5 to 30 percent by volume of n-paraffins and 70-97 percent by volume of said aromatic hydrocarbon at a temperature above 60° C. but below the dissociation temperature of said adduct, and

(e) separating thus regenerated urea from the liquid mixture.

2. Process according to claim 1 which is continuous and wherein said n-paraffins in said decomposition medium are obtained from a previous separation of said hydrocarbon oil by urea adduction, and wherein regenerated urea from step (e) is recycled and used to treat said hydrocarbon oil in step (a).

3. A process according to claim 1 and the further step of retreating said adduct separated in step (b) by vigorously agitating said adduct with 1.5 to 5 volume of a contact oil per volume of adduct, said contact oil being selected from at least one member of the group consisting of a hydrocarbon charge oil, n-paraffinic oil, a mixture of hydrocarbon charge oil and aromatic hydrocarbon of 6 to 8 carbon atoms, and a mixture of n-paraffinic oil and aromatic hydrocarbon of 6 to 8 carbon atoms.

4. A continuous process for the separation of n-paraffins from a distillate hydrocarbon oil by means of powdered urea, which comprises

(a) vigorously agitating said hydrocarbon oil with said urea in the presence of an activator solvent consisting essentially of 3 to 30 percent by volume of methanol and 70 to 97 percent by volume of aromatic hydrocarbon having from 6 to 8 carbon atoms per molecule, said activator solvent being present in an amount of 5 to 40 percent by volume based on the volume of said hydrocarbon oil to form an n-paraffin-urea adduct,

(b) separating said urea adduct from the liquid mixture,

(c) retreating said adduct by vigorously agitating said adduct with 1.5 to 5 volumes of a contact oil per volume of adduct, said contact oil being selected from at least one member of the group consisting of hydrocarbon charge oil, n-paraffinic oil, a mixture of hydrocarbon charge oil and aromatic hydrocarbon of 6 to 8 carbon atoms, and a mixture of n-paraffinic

oil and aromatic hydrocarbon of 6 to 8 carbon atoms,

(d) separating retreated adduct from said contact oil,

(e) washing said adduct with said aromatic hydrocarbon,

(f) decomposing said adduct by heating a mixture of said adduct and 1.5 to 5.0 volumes per volume of said adduct in a decomposition medium consisting essentially of 5 to 30 percent by volume of n-paraffins and 70-97 percent by volume of said aromatic hydrocarbon at a temperature above 60° C. but below the dissociation temperature of said adduct,

(g) separating thus regenerated urea from the liquid mixture, and

(h) recycling said regenerated urea.

5. A continuous process according to claim 4 wherein said contact oil for the retreatment of said urea adduct is n-paraffins oil which has been obtained from charge hydrocarbon oil by urea adduction.

6. A continuous process according to claim 4 wherein said contact oil for retreatment of said urea adduct is n-paraffin oil comprised of a mixture of n-paraffins previously separated from hydrocarbon charge oil by urea adduction and paraffinic hydrocarbon having 5 to 8 carbon atoms.

7. A continuous process according to claim 4 wherein said contact oil for retreatment of said urea adduct is a mixture of n-paraffins previously separated from hydrocarbon charge oil and aromatic hydrocarbon having 6 to 8 carbon atoms.

8. A continuous process according to claim 4 wherein said contact oil for the retreatment of said urea adduct is hydrocarbon charge oil.

9. A continuous process according to claim 4 wherein said contact oil for retreatment of said urea adduct is a mixture of hydrocarbon charge oil and n-paraffinic oil.

10. A continuous process according to claim 4 wherein said contact oil for retreatment of said adduct is a mixture of hydrocarbon charge oil and aromatic hydrocarbon of 6 to 8 carbon atoms.
